INVENTOR:
Harry G. Ainsworth,
By *Robert Brown*
his Atty

UNITED STATES PATENT OFFICE.

HARRY G. AINSWORTH, OF KENTLAND, INDIANA.

GARAGE DOOR.

Application filed April 6, 1923. Serial No. 630,403.

To all whom it may concern:

Be it known that I, HARRY G. AINSWORTH, a citizen of the United States, residing at Kentland, in the county of Newton and State of Indiana, have invented certain new and useful Improvements in Garage Doors, of which the following is a specification, reference being had to the accompanying drawings, and to the reference characters marked thereon, which form a part of this specification.

This invention relates to improvements in automatic devices for opening and closing doors and more particularly to doors on barns and garages.

The principal object of the invention is to provide a door opening mechanism that may be put in operation from the outside of the door-closed building, by merely operating a switch or push button in an electric circuit. Another object is to provide a mechanism of the class described which may be set in operation by the occupant of an automobile or other vehicle without leaving the latter. Another object of the invention is to adapt the door opening mechanism to a plurality of doors, actuated by the electrical energy supplied from a single source of supply. A further object of the invention is to furnish a mechanism of the class described, which will be of the simplest possible construction, easy to install, not liable easily to get out of order, positive in operation, and cheap to manufacture, and therefore not only within the reach of all but also fool-proof and readily operated by unskilled persons.

These and other objects and advantages of the invention will be more readily comprehended as I proceed with my specification,—the invention consisting in the devices herein illustrated, described and claimed.

In the drawings, wherein I have shown one embodiment of my invention:

Fig. 1 illustrates the inside of a garage or other building, equipped with my invention, the inside of the doors and end of the building being in elevation.

Fig. 2 is a horizontal sectional plan view of the same, taken upon the plane indicated by the dotted line 2—2 of Fig. 1, looking down as indicated by the arrows.

Fig. 3 is a vertical sectional view of the same, taken in the plane indicated by the

dotted line 3—3 of Fig. 2, and looking in the direction shown by the arrows.

Fig. 4 is a view, enlarged, of a part of the operating shaft, and the contact brush arm attached thereto, the regulator and supporting bracket being in section taken in the plane of the dotted line 4—4 of Fig. 2.

Fig. 5 is a face view of a regulator and contact brush, and lay-out of the electric circuit.

Fig. 6 is a plan view, enlarged, of the hinge toggle arm connections, looking down as indicated at 6—6 in Fig. 7.

Fig. 7 is a side view of the same.

Fig. 8 is a view of the door connection showing its adjustable feature.

In said drawing, A represents a garage or other building, as a whole, having in its end wall *a* the doors *b*, *c*, hinged at *d* to a suitable door opening, side walls *e*, *f*, and a top *g*. To the ceiling or top wall *g* is secured, by a bracket 1, a motor *M*, provided on its shaft with a worm 2. An operating shaft 3, carrying a worm gear 4, is suitably mounted in brackets 5, 5, from the ceiling *g*, and projects at its ends beyond the end bracket 5, so as to have mounted thereon a crank arm 6. As there are two doors *b*, *c*, so there are two crank arms 6, 6,—one at each end of the shaft 3. These crank arms 6, 6, are adjustably mounted by means of the nuts 7, 7. A lifting rod 8 is pivotally connected at its upper end to the free end 9 of the arm 6, while the lower end of the rod 8 is provided with an apertured disc 10, and is pivotally connected to devices attached to the door and to a wall or fixed support in any suitable or convenient manner. One such means of connection is herein illustrated as follows. To similar and interlocking lugs 11, the said lug 10 is pivotally secured by the pin or pivot bolt 12, constituting a hinge, indicated as a whole at 13. The attaching plate member 14 of the hinge is adjustably connected to a staple 15 on the side wall *e*, while the other plate member 16 is similarly connected to a staple 17 on the back of the door *b*.

The connecting means comprises a hook member 18 adapted to engage the staple 15 and exteriorly screw threaded on its unhooked end; a plate 19 secured by screws 20 or otherwise to the plate member 14, said plate 19 having an exteriorly screw threaded end member 21; and an adjusting nut 22.

threaded interiorly. The threaded ends of the members 18 and 21 are adapted to enter the nut 22 and by right and left hand threading, are suitably adjusted towards or 5 from each other, in a familiar manner.

The connection of the plate member 16 to the staple 17 on the door *b* is similar, and the description need not be repeated.

When the shaft 3 is actuated, the crank 10 arm 6 is rocked, raising the lifting rod 8. This rod 8, in turn lifts up the two pivotally connected plate members 14, 16, and the intermediate parts connecting them to the wall staple 15 and the door staple 17, carrying 15 them from the position shown in full lines to that shown in dotted lines in Fig. 1. This toggle action necessarily exerts a pull or tension upon the door *b*, resulting in the swinging of the door upon its hinges until 20 the door is opened.

A similar set of devices is used when there are double doors, and as shown, the door *c* will be similarly connected up and operated as just explained with respect to the door *b*.

The shaft operating motor is connected in circuit with switches or push buttons and a battery or other suitable source of electrical energy, and the switches or push buttons are located upon the outside of the 25 garage or other building in any desired position. I have not attempted herein to illustrate such location with respect to the door, as it will readily be understood that the location of a particular switch or push 30 button is incidental to the invention and will be positioned to suit the special requirements of each installation. For example, one switch may be inside the garage so that the operator may get into his automobile, 35 push the switch, have the door automatically open and then drive out. He may have a second switch on the outside, which upon being pressed will start the mechanism in motion and have the door closed behind 40 him. He may have a second switch on the outside, so that he may open the door to drive into the garage and a second switch on the inside to close the door. It will be 45 understood, of course, that he may have a 50 multiple switch instead of a plurality of single switches.

The electric circuit illustrated in Fig. 5 is as follows: Upon the shaft 3 is secured a regulator disc *R*, one face of which is provided with a central concentric ring *R'*, and two outer concentric half rings *R²*, *R³*. Mounted upon the shaft, but suitably insulated therefrom, is a brush arm *B* having electrical contact with the rings *R'*, and *R²*, or *R'* and *R³*, according to the position, 55 at the time, of the brush *B*. Suitable switches or push buttons *S'*, *S²*, and *S³* are located where convenient. For example, in the particular installation herein illustrated, switch *S'*, is a conventional type of

three-way switch, and *S²* and *S³* are four-way switches. *L'*, *L²*, *L³*, *L⁴* are lines for the current, *L³* connecting the motor *M* with the ring *R'*, while lines *L²* and *L³* connect the switches with the rings *R²* and *R³*, respectively. Contact points *p*, *p'*, *p²*, *p³*, for example, are adapted for use with the switch *S'*.

As shown in the diagrammatic view, Fig. 5, the current will flow along line *L'* to *p*, to *p'*, to line *L²*, ring *R²*, brush *B* to ring *R'*, line *L³* through motor *M* and to line *L⁴*. This will cause the motor to operate and through the worm and worm-gear, rotate the shaft 3, thereby raising the crank arm 6, the lifting rod 8 and the toggle connections to open the door *b*. If now the switch *S'* be turned so as to break at *p* and *p'* and contact with the points *p²* and *p³*, the current will flow from *L'* to *p*, *p²*, *p³*, *L³*, ring *R³*, brush *B*, ring *R'*, *L³* to motor *M* and line *L⁴*, thus again operating the shaft 3 and turning the crank arm 6 down, thereby pushing the rod 8 and toggle connections down to cause the door to close.

If there be a pair of doors, and similar devices to those described for one door, connect the second door and the shaft 3; then both doors may be opened and closed simultaneously.

It is desirable to have a tension device of some sort to exert pressure upon the back of the open door, when the rod is lowered for the door closing operation. One form of such is illustrated herein in Figs. 2 and 3, and comprises a yielding or spring pressed arm 23 pivotally secured at 24 to a fixed support, such as bracket 25 on the wall. This arm has an antifriction roller 26 on its outer end to contact with the door and its other end 27 presses upon a tension spring 28, said spring being connected at its other end to the support or bracket 25. When the door *b* is opened, it presently contacts with the roller 26 and moves the arm 23, 27, about its pivot against the pressure of the spring 28. When the door mechanism is actuated to close the door, the tension of the spring 28 exerts a strong pressure on the arm 23, 27, returning the latter to its normal position, thus facilitating the movement of the door and preventing any tendency to "dead center" in the toggle link mechanism.

It will be understood that to avoid accident or for any other purpose, movement of the door may be arrested before being completely opened or closed by simply pressing the operating switch or button a second time. Also that the door starts to open gradually and increases its motion as the movement continues, and that in closing the door, the movement starts rather rapidly and slows down, so that the door closes gently and without jarring. It will also be noticed that since the connection 17 is at

- the middle of the door *b* there is a lifting tendency upon the door as a whole, which prevents its lower edge from binding or scraping on the floor. Thus the door is moved easily and there is no tendency to wrench it out of shape or bring undue strain upon its hinges. The entire device is simple, easily operated by a mere novice and does not get out of order.
- 5 10 It will be understood that modifications may be made in the various details of the device without departing from the scope and spirit of my invention. Nevertheless, as a result of the successful operation of this device in use, I recommend the foregoing form in which I have illustrated my invention. However, I do not desire my invention to be limited to the details of form and arrangement shown and described, except as pointed out in the claims.
- I claim as my invention:
1. A door opening and closing device of the character described, comprising a fixed support, a rotatable shaft mounted thereon, 25 electrically operated means for actuating said shaft to rotate in one direction, a crank on the shaft, a lifting rod connected with the crank and actuated by the movement of the shaft, a hinged door and adjustable operative toggle connections between the end 30 of the rod and the door.
  2. A door opening and closing device of the character described, comprising a fixed support, a rotatable shaft mounted thereon, 35 electrically operated means for actuating said shaft to rotate always in the same direction, a crank mounted directly upon the shaft, a lifting rod connected at one end with the crank and actuated by the movement of the crank, a hinged door, and two hinged link members connected to said lift-
- ing rod, the end of one member being secured to the door and the end of the other link member being secured to the fixed support.
3. A door opening and closing device of the character described, comprising a fixed support, a rotatable shaft mounted thereon, electrically operated means for actuating said shaft to rotate always in the same direction, a crank mounted directly upon the shaft, a lifting rod connected at one end with the crank and actuated by the movement of the crank, a hinged door, and two hinged link members connected to said lifting rod, the end of one member being secured to the door and the end of the other link member being secured to the fixed support, and means for adjusting one of said link members.
4. The door opening and closing device of the character described, comprising a rotatable shaft, electrically operated means for actuating said shaft, a lifting rod connected with and actuated by the movement of the shaft, and connections between the end of said rod, the door to be operated and a fixed support, said electrically operated means including an electric circuit, two terminal connections, a suitable switch button, and a brush arm on said shaft in contact with one side of the circuit and adapted also to contact with either one of the terminal connections.

In testimony that I claim the foregoing as my invention I affix my signature, in the presence of two witnesses, this 31st day of March, 1923.

HARRY G. AINSWORTH.
